FREQUENCY CONVERTERS USING A TRANSMISSION LINE IMPEDANCE TRANSFORMER
Richard W. Anderson, Los Altos, Calif., assignor to Hewlett-Packard Company, Palo Alto, Calif., a corporation of CaliforniaFiled Apr. 12, 1963, Ser. No. 272,671
4 Claims. (Cl. 325—445)

This invention relates to apparatus for mixing selected frequencies to obtain an intermediate frequency with negligible loss of signal power.

The principal object of the present invention is to provide apparatus for selecting and mixing applied signals with a minimum of signal power loss.

It is another object of the present invention to provide improved signal filtering and mixing apparatus.

In accordance with the illustrated embodiment of the present invention a pair of cavities are connected to receive an applied signal and a local signal and are adapted to resonate at frequencies which are separated by a desired output frequency. The cavities are coupled together using a cable having a length which is a selected multiple of half wavelengths of the applied signal. The ends of the cable form coupling loops within the cavities. One 20 end of the cable passes through the cavity connected to receive the applied signal and connects to a mixing element. Thus the signal coupled to the cable from one cavity and the signal from the other cavity are combined in a mixing element to form the desired output frequency.

Referring to the drawing, there is shown a local oscillator 9 coupled into cavity 11 by a harmonic generator 13 and a coupling loop 15. Applied signal appearing at input 17 is coupled into cavity 19 by coupling loop 21. The cavities are connected together by a cable 23, one end of which forms a shorted coupling loop 25 within cavity 11. The other end of cable 23 passes through the cavity 19, forms a coupling loop 27 therein and connects to mixing element 29. The local oscillator 9 and harmonic generator 13 produce a signal frequency which resonates in cavity 11. A portion of this signal is picked up by coupling loop 25 and is applied directly to the mixing element 29 by the cable 23. To this signal there is applied the resonant frequency of the signal within cavity 19. Mixing element 29 combines these signal frequencies and produces an output signal as a selected modulation product of the two signals. The length of the cable 23 is selected to be substantially equal to a number of half wavelengths of the signal frequency of the resonant cavity 19. Thus, for the values indicated, the length of line 23 may be chosen as ten half wavelengths of the signal of cavity 19. This length of line is thus one half wavelength at the frequency of the output signal. Since the cable is shorted at one end by coupling loop 25, the signal in cavity 19 also sees a shorted cable a number of half lengths away from this shorted end. Thus substantially none of the signal power from the applied signal of 17 is coupled from cavity 19 to the cavity 11 along cable 23. The other end of cable 23 is not shorted but rather is terminated in the impedance of the mixer element 29. Thus the signal in cavity 11 also sees this impedance at the coupling loop 25 a selected number of half wavelengths away along cable 23.

2

The signal coupled from cavity 11 and applied to the mixer element 29 through cable 23 appears with sufficient signal level to properly bias the diode 31 within the mixer element for high sensitivity detection. Applied signals appearing in cavity 19 at low power levels are adequate to produce the desired output signal once the diode is biased to maximum sensitivity. Further, since the end of cable 23 within the cavity 19 appears as a short to the signal within that cavity, substantially the entire applied signal appears at the output and negligible applied signal power is lost in the cable and cavity 11.

The circuit of the present invention thus provides high selectivity of the frequencies to be mixed and provides high sensitivity to applied signal using only a minimum of local signal power.

I claim:

1. Signalling apparatus comprising:
an input and a source of signal;
a first cavity resonator connected to the input for receiving an input signal and a second cavity resonator connected to receive the signal from said source;
the first and second cavities having resonant frequencies which are separated by a selected frequency value;
a signal mixer element;
an electric wave transmission line having one end disposed in signal coupling relationship to the second cavity resonator and having a portion thereof disposed within said first cavity resonator in signal coupling relationship therewith with another end connected to said signal mixer element;
said transmission line having a length between the first and second cavity resonators which transforms the impedance presented by said second cavity resonator to signal on said transmission line having a frequency equal to the resonant frequency of said first cavity substantially to a short at the location of said portion of the transmission line which is coupled to said first cavity; and
means connected to said signal mixer element for producing an output signal of said selected frequency value.

2. Signalling apparatus comprising:
an input and a source of signal;
a first cavity connected to said input and a second cavity connected to said source, said cavities being adapted to resonate at frequencies which are separated by a selected frequency value;
an electric wave transmission line connecting said cavities;
one end of said transmission line being disposed within the second cavity and forming a shorted coupling loop therein;
a mixer element, a portion of said transmission line being disposed within the first cavity to form a coupling loop therein with the end of said transmission line connected to said mixer element;
the length of said transmission line between cavities being substantially equal to a selected multiple of one half wavelength of signal in said transmission line having said selected frequency value; and
means connected to said mixer element for producing an output signal of said selected frequency value.
3. Signalling apparatus as in claim 2 wherein one of

the first and second cavities resonates at a frequency for which said transmission line between cavities is an integer multiple of half wavelengths.

4. Signalling apparatus as in claim 3 wherein:

the length of said transmission line between cavities is altered from substantially ten half wavelengths at the resonant frequency of said first cavity to transform the impedance presented by said second cavity at the frequency of resonance of the first cavity substan-

5

tially to a short circuit at the location along the transmission line disposed within the first cavity.
